CLAIM

The ornamental design for a display screen with a graphical interface, as shown and described.

DESCRIPTION

FIG. 1 is a perspective view illustrating a display screen with a graphical interface according to one embodiment; and, FIG. 2 is a front view illustrating thereof.

The broken line showings of the display screen, rectangles, and triangle the figures are included for the purpose of illustrating environmental structure and portions of the display screen with a graphical interface. The broken lines form no part of the claimed design.

1 Claim, 2 Drawing Sheets
